UNITED STATES PATENT OFFICE

JEAN BAPTISTE ICRE, OF NEW YORK, N. Y.

OVEN

Application filed June 16, 1930. Serial No. 461,324.

My invention relates to ovens, and while designed primarily for use in baking ovens, is applicable to other cases in which articles or goods are to be subjected to heat for a relatively considerable length of time, as in metallurgy and ceramics. The object of my invention is to provide an improved oven of this character, having novel means for causing the articles or goods to travel within the oven, a novel heating arrangement, and other features of novelty which are disclosed in the accompanying drawings and in the specification following hereinafter, and particularly pointed out in the appended claims.

Reference is to be had to the accompanying drawings illustrating, as an example, a satisfactory and preferred embodiment of my invention. Fig. 1 is a front elevation of the improved oven; Fig. 2 is a vertical section on line 2—2 of Fig. 1; Fig. 3 is a section on line 3—3 of Fig. 2; Fig. 4 is a detail side elevation; Fig. 5 shows an auxiliary furnace, and Fig. 6 a section of the same; Fig. 7 is a detail sectional view of one of the traveling carriers which convey the goods within the oven; Fig. 8 is a section on line 8—8 of Fig. 7; Fig. 9 is a horizontal section on line 9—9 of Fig. 8; Fig. 10 is a detail of the carrier; Fig. 11 is a vertical section on line 11—11 of Fig. 2; Fig. 12 is a horizontal section on line 12—12 of Fig. 14; Fig. 13 is a top view of the oven; Fig. 14 is a rear elevation thereof; and Fig. 15 is a side elevation of the oven.

The masonry or brickwork constituting the body of the oven comprises a top wall 30, a rear wall 31, a bottom 32, and side walls 33. The front of the oven is normally closed by four doors, viz. two upper doors 34 hinged on the side walls at 35, and two lower doors 34' hinged at 35'. These doors are held in their normal closed position by nuts and bolts 36 co-operating with bars or strips 37 which also serve to cover the meeting edges of the doors and thus to produce tight joints. The lower doors 34' have openings 34'' adapted to be closed by vertically movable slides or auxiliary doors 38 arranged between the outer faces of said doors 34' and guide walls or plates 39. The slides 38 are connected by rods 40 with cross members or

heads 41 each connected by a cable 42 or the like with a counterweight 43, the cables passing over guide pulleys 44 journaled in brackets 45. The two slides 38 when fully lowered completely close the two openings 34''. In certain cases, as referred to hereinafter, a platform P may be slid into the lower half of the opening 34'', in which case the slides 38 are lowered only to contact with the said platform, as shown in Fig. 2. The counterbalancing of the slides enables the attendant to move them readily up or down, as desired. The doors 34, 34' are opened only on rare occasions, as for overhauling or general cleaning.

Within the chamber formed by the walls of the oven are located carriers for the articles to be treated, and parts of mechanism for giving said carriers an intermittent movement, first upwardly in a succession of stages, then transversely in one direction, then downwardly in a series of steps, and finally transversely in the opposite direction. The carriers may be of any suitable construction; for instance, they may consist of shallow troughs each comprising a horizontal bottom wall 46 and upward flanges 46', 46'' at the side and rear edges respectively of said bottom, there being no such flange at the front, which is open (see Fig. 2). The troughs might serve directly as supports for the articles to be treated in the oven, but in the example illustrated, such articles are intended to be placed on trays 47 which rest on said troughs 46, 46', 46'' removably, said trays being provided with rollers 48 traveling on the bottom 46 adjacent to the side flanges 46'. The latter may extend upwardly into recesses or housings 46a. With this particular construction, the trays are substantially of the same length and width as the carriers.

Each carrier is provided, at the center of each of the side walls or flanges 46', with brackets 49 extending upwardly and provided with aligning rollers 50 which are adapted to rest, at times, in supports 51 forming extensions on the central portions of the links of two endless chains 52, each located adjacent to one of the side walls 33. The

pivots of the chain links are indicated at 52'. Each chain has an ascending run and a descending run, adapted to move between stationary guides 53. The chains 52 pass over sprockets 54.

A pair of horizontal upper conveyers 55 are arranged adjacent to the upper ends of the ascending and the descending runs of the chains 52, and is intended to transfer carriers, in the manner set forth hereinafter, from the upper end of the ascending run to the upper end of the descending run. Each of said conveyers 55 has projections 55' adapted to engage the rollers 50 at certain times, for shifting the carriers 46 transversely; during such transverse movement, the rollers 50, as soon as they pass out of openings 51' at the sides of the supports 51, travel and rest on stationary horizontal upper supports 56 which are parallel to the runs of the upper transferring conveyers 55. As shown in Fig. 7, I prefer to make each of the supports 51 at its central portion with two superposed concave portions or recesses forming seats for the rollers 50, so as to prevent any accidental slipping of said rollers through the lateral openings 51'. The distance between these two seats is considerably greater than the diameter of a roller 50, while the width or rather height of the lateral openings 51' is just sufficient to permit the roller to pass therethrough. If we assume that Fig. 7 shows a portion of the descending chain run, it will be obvious that when this same chain portion during the further travel of the chain becomes part of the ascending chain run, the roller 50 will engage, and be supported by, that concave seat which in Fig. 7 is above the roller, but which on the ascending chain run comes below the roller.

Similarly, at the lower portion of the oven, a pair of horizontal lower conveyers 57 are provided for transferring the carriers 46 from the lower portion of the descending runs of the chains 52, to the lower portion of the ascending runs of said chains. For this purpose, each of the conveyers 57 has projections 57' adapted to engage lugs 49' on the brackets 49, to move the carriers 46 transversely, during which transverse (horizontal) movement the carriers are supported by stationary tracks 58 engaged by rollers 46b journaled on said carriers, the side walls 33 having horizontal grooves 33' for the passage of the rollers 50.

The upper conveyers 55 pass over sprockets 55'', and the lower conveyers 57 over sprockets 57''. Sprockets 59, 60 are held to rotate in unison with one of the sprockets of an upper and a lower conveyer respectively, and these sprockets are connected by a chain 60', while the two upper conveyers are connected by having two corresponding sprockets 55'' mounted rigidly on the same shaft, a similar arrangement being employed

with respect to the two lower conveyers 57. Thus the four conveyers 55, 57 will be caused to move in unison. Any other suitable mechanism may be employed for accomplishing this result. The two chains 52 are suitably connected so that they will move in unison, for instance by mounting corresponding sprockets 54 of the two chains on the same shaft.

The chains 52 may be driven by a motor 61 (for instance an electric motor) with the aid of a worm drive 62. As it is intended to give a step-by-step movement to the carriers 46, I prefer an arrangement which will at each step give the chains 52 automatically a movement of just the right extent. For this purpose, I may employ a pedal 63 controlling, by intermediate connections 63', a clutch 64 of the well-known one-revolution type; that is to say, the motor 61 would run continuously, but would normally be disconnected from the worm drive 62 operating the chains 52. Upon pressing the pedal 63, the clutch 64 would be thrown in, and the drive 62 actuated to impart motion to the chains 52. After one revolution (this being sufficient to give the chains 52 the feed movement for one step) the clutch 64 would be thrown out automatically, as is well-known in clutches of this type, and the movement of the chains 52 would stop. Similarly, an electric (or other) motor 65 might, through a one-revolution clutch 66, actuate a worm drive 67 operating the connected upper conveyors 55 and lower conveyers 57, and at each operation drive them just to the proper extent for transferring a carrier 46 (at the top) rearwardly from the upper end of the ascending runs of the chains 52 to the upper end of their descending runs, while at the same time another carrier would be conveyed (at the bottom) forwardly from the lower end of the descending runs of the chains 52.

It is desirable that the operation of the conveyers 55, 57 should begin automatically as soon as the movement of the chains 52 has stopped. For this purpose, I may, for instance, provide on the one-revolution clutch 64 a cam 68 arranged to throw in the one-revolution clutch 66 at the end of the one revolution of clutch 64. Thus depression of the pedal 63 would first start the chains 52, and after said chains have moved to the desired extent (one step), they would stop, and simultaneously with such stoppage the conveyers 55, 57 would be started automatically, to stop after a movement of predetermined extent. The chains and conveyers would then remain stationary until the operator again depresses the pedal 63. A spring (not shown) or other expedient would return the pedal to its normal (raised) position.

In some cases, I may wish to have the alternate movements of the chains 52 and conveyers 55, 57 repeated automatically until

the operator stops such repetition. For this purpose, the lever 69 which is actuated by the cam 68 to shift the clutch 66, may be connected temporarily, as by a link 70, with the pedal 63 or its connection 63'. These parts would be so constructed and arranged that when the lever 69 moves to throw out the clutch 66, it would at the same time automatically move the pedal connections 63' in such a direction as to throw in the clutch 64 and thus again start the chains 52. As long as the link 70 remains connected as described, the intermittent movement of the chains 52 and conveyers 55, 57 would continue in regular alternation. If however, the link 70 is disconnected, depression of the pedal will cause just one movement of the chains 52, followed by one movement of the conveyers 55, 57, whereupon these parts will stop.

For heating the oven, I have provided a furnace 71 having a door 72 at the front of the oven, with a grate 73 and a combustion chamber 74. From the latter a wide central horizontal flue 75 and diverging horizontal flues 75' extend to the rear wall of the oven. From the combustion chamber 74 diverging horizontal flues 76 extend to bottom flues 77 located in the side walls 33 and extending from front to rear. At their rear ends, the flues 77 communicate with uptakes 78, from the upper ends of which flues 79 extend forwardly to the lower ends of uptakes 80, the upper ends of which communicate with horizontal flues 81 extending rearwardly. At the rear ends, the flues 81 communicate with uptakes 82, from the upper ends of which horizontal flues 83 extend forwardly, to communicate with short uptakes 84, the upper ends of which communicate with transverse horizontal flues 85 located on the top wall 30 and communicating with the stack 86. At the rear ends of the flues 75', uptakes 87 lead therefrom in the rear wall 31 to horizontal flues 88 extending forwardly in the top walls 30. From the front ends of said flues 88, horizontal flues 89 extend obliquely rearward, to communicate with forwardly extending horizontal flues 90 leading to the stack 86. From the interior of the oven, near the rear thereof, an uptake 91 leads to a horizontal flue 92 located in the top wall 30 and extending to the stack 86. At the rear of the central horizontal flue 75, two uptakes 93 forming dead spaces extend upwardly in the rear wall 31 to about half its height. Suitable doors 94 are located at the ends of flues, for normally closing openings through which access may be had to such flues for cleaning them. At 95 I have indicated adjustable dampers for regulating the draft and the distribution of the heating gases among the several flues.

In the side walls 33, I have provided two small auxiliary furnaces 96, with ducts or flues 97 leading therefrom to the interior

of the oven, at the lower portion thereof.

In addition to the above-described means for heating the furnace by combustion, I have provided electrical heaters 98 associated with the several carriers 46 and arranged to travel therewith. For instance, these heaters may be secured to the bottom of each carrier and be of the well-known type embodying a resistance wire imbedded in a suitable insulating body. Current is supplied to the heaters in any suitable manner, for instance by conducting rollers 99 moving with the carriers 46 and connected with the ends of the resistance wire, said rollers being pressed by springs 100 against conducting tracks 101 to which electric current is supplied from any suitable source.

The operation is as follows when the oven is used for baking, which is the purpose for which my invention has been designed primarily: The trays 47 are filled with bricks B or other heat retaining material, and the dough in the form of loaves or other articles to be baked is preferably placed in pans A, outside the oven, and these loaded pans are then placed on top of the bricks B as shown in Fig. 11. The pans are placed on the trays while the latter are still outside the oven and the slides 38 are raised so that the trays with the loaded pans may be introduced into the oven and brought to rest on the carrier 46 which is in the lowermost position at the ascending portion of the chains 52. In carrying out this loading operation, it may be convenient to roll the trays over a platform P which is placed temporarily in the lower portion of the openings 34" as shown in Fig. 2. The main furnace 71 and if desired the auxiliary furnaces 96 are then started to heat the walls of the oven to the proper temperature. The interior of the oven will, of course, at that time not be heated to the same temperature as the oven walls themselves. At a suitable time, the operator will connect the conducting tracks 101 with the source of electric current, as by throwing a suitable switch (not shown) so that the heat developed by the electric heaters 98 at the bottom of the carriers 46 will be added to that produced by the combustion gases, and thus when the electric heaters are operative, the temperature within the oven will be higher than the temperature of its walls, so that the baking of the bread or the like will take place properly.

After the carrier 46 which is at the bottom, near the openings 34", has been loaded as described, and the slides 38 lowered, by the attendant, and while the link 70 is disconnected, the pedal 63 is depressed so that by the mechanism described above, the one-revolution clutch 64 is thrown in and the chains 52 given a longitudinal movement of proper extent to lift said loaded carrier 46 one step, that is to say to bring such carrier to the po-

sition shown in Fig. 2 for the carrier immediately above the lowermost. While one vertical run of the chains is ascending, their other vertical run is descending thereby bringing a carrier in the descending column to the bottom position. At the end of this upward motion of the loaded carrier, the horizontal conveyers 55 and 57 will automatically receive a longitudinal motion by which, as regards the upper conveyor 55, the uppermost carrier 46 of the ascending column will be shifted rearwardly to bring it into registry with the descending column, while the lowermost carrier 46 of the descending column will be shifted forwardly to bring it adjacent to the openings 34". The conveyors 55 and 57 then stop and the attendant may open the slides 38 to remove the pan A if the bread is fully baked, and to insert in place of such removed pan, another containing loaves to be baked. This operation is continued step by step as required. After all the carriers 46 have been loaded, it may be desired to have them make more than one complete circuit of the oven interior, and in order that this may be accomplished without requiring the attendant to press again on the pedal 63, the link 70 may be connected as described above, and after this has been done, the vertical movement of the ascending and descending runs of the chains 52, alternating with the horizontal movement of the conveyers 55 and 57, will go on as long as the link 70 remains thus connected. The operation will then be stopped by the operator as soon as he judges that the proper time has arrived, by disconnecting the link 70 and then bringing the pans A successively to the proper position for discharge through the openings 34", in the manner described above, at a time when both the chains 52 and the conveyers 55 and 57 are stationary. When this position for discharge is reached, there will be no carrier 46 at the bottom of the right hand or descending column (Fig. 2) and no carrier 46 at the top of the left hand or ascending column.

In order that the temperatures within the walls of the oven and in the interior of the oven may be ascertained at any time, thermometers such as indicated at T and T' may be provided.

I may also, without employing the main furnace 71 and the flue system connected therewith, simply heat the interior of the oven by the auxiliary furnaces 96, and if desired also give additional heat to the carriers 46 by means of the electric heaters 98.

An oven having the features disclosed herein may be used for baking, or for many other operations where articles are to be subjected to heat for a certain length of time; among such operations I may mention annealing of metal articles, the heating of ceramic products, the drying of various articles, etc.

In order to prevent overheating of the door 72, I may provide lateral flues 102 which will carry off the excess heat, say to the horizontal flues 77.

The new oven is very compact, requires much less floor space than ovens of the usual type, and is very economical in fuel consumption. The output of the oven in the unit of time is greater than in prior constructions. All parts are readily accessible upon opening the doors, no taking down or apart being required.

Various modifications may be made without departing from the nature of my invention as set forth in the appended claims.

I claim:

1. An oven provided in its interior with an endless chain having ascending and descending runs, carriers connected with said chain pivotally and slidably laterally, and provided with rollers, an upper conveyer for transferring carriers from the ascending chain run to the descending one, a lower conveyer for transferring carriers from the descending chain run to the ascending one, a track engaged by said rollers during the transfer of a carrier from one of said chain runs to the other and arranged adjacent to the conveyer effecting such transfer, and co-ordinated means for operating said chain and conveyers in properly timed sequence.

2. An oven provided in its interior with an endless chain having ascending and descending runs, carriers pivotally connected with said chain and slidably relatively thereto to detach them from the chain, or connect them therewith, an upper conveyer for transferring carriers from the ascending chain run to the descending one, a lower conveyer for transferring carriers from the descending chain run to the ascending one, an operative connection for causing the two transferring conveyers to move in unison, and means for operating said chain and conveyers.

3. An oven according to claim 2, in which mechanism is provided to move the chain a predetermined distance, and then, while the chain is stationary, automatically give said conveyers their transferring movement.

4. An oven according to claim 2, in which mechanism is provided to move the chain intermittently, and, during the intervals when the chain is stationary, automatically give said conveyers their transferring movement, said mechanism including a member arranged to be thrown out of operative position, to substitute selectively, for the intermittent chain movements alternating with conveyer movements, a single chain movement followed by a single movement of the conveyers.

5. An oven provided in its interior with an endless chain having pivotally-connected links, supports located on said links between

adjacent chain pivots, and carriers hung on said supports pivotally so that such carriers may always remain in a substantially horizontal position, and also having a sliding connection with said supports so that the carriers may be given a lateral movement to connect them with the chain or disconnect them therefrom.

6. An oven provided with an internal end-
10 less chain having pivotally-connected links, supports located on said links and provided with lateral openings and with concave seats adjacent to such openings, and carriers provided with pivots adapted to engage said supports at such concave seats to hang the carriers in a substantially horizontal position, said carrier pivots having a sliding connection with said supports to pass in and out through said lateral openings, so that the carriers
15 may be given a lateral movement to connect them with the chain or disconnect them therefrom.

In testimony whereof I have hereunto set my hand.
